US00D587590S

(12) **United States Design Patent**
Crawford et al.

(10) **Patent No.:** US D587,590 S
(45) **Date of Patent:** ** Mar. 3, 2009

(54) **CONTAINER**

(75) Inventors: **John C. Crawford**, Mahopac, NY (US);
Roland Charriez, Mohegan Lake, NY
(US)

(73) Assignee: **Colgate Palmolive Company**, New
York, NY (US)

(**) Term: **14 Years**

(21) Appl. No.: **29/278,212**

(22) Filed: **Mar. 22, 2007**

(51) LOC (9) Cl. **09-01**

(52) U.S. Cl. **D9/563**; D9/550; D9/558;
D9/564; D9/574

(58) **Field of Classification Search** D9/682,
D9/685-686, 689, 516, 529-530, 537-543,
D9/549-550, 558, 563, 574; 215/381-385;
220/660, 669, 675

See application file for complete search history.

(57) **CLAIM**

The ornamental design for a container, as shown and described.

DESCRIPTION

FIG. 1 is a perspective view of the container of our design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof; and,

FIG. 7 is a bottom plan view thereof.

The broken line showing of the bottom of the container is for illustrative purposes only and forms no part of the claimed design.

1 Claim, 6 Drawing Sheets
